UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN, A CORPORATION OF MICHIGAN.

FOLDING MECHANISM FOR WEB-PRINTING PRESSES.

No. 806,369.

Specification of Letters Patent.

Patented Dec. 8, 1908.

Application filed May 2, 1907. Serial No. 371,491.

To all whom it may concern:

Be it known that I, HENRY F. BECHMAN, of Battle Creek, in the county of Calhoun and State of Michigan, have invented certain new and useful Improvements in Folding Mechanisms for Web-Printing Presses; and I hereby declare that the following is a full, clear, and exact description thereof, reference being had to the accompanying drawings, which form part of this specification.

This invention is an improvement in folding mechanisms for newspaper web-printing presses, and its object is to provide means whereby sheets may be directed either from the second-fold rolls to the stacker to be delivered folded half-size, or may be passed on to the third-fold rolls and be delivered folded one-fourth size; and for this purpose I provide a series of tapes which may be adjusted into different positions, so as to either direct the papers from the second-fold rolls to the third-fold rolls; or permit them to pass direct from the second-fold rolls to the stacker.

The invention consists in the novel arrangement of such tapes and means for adjusting them as will be fully understood from the following description in connection with the drawings, in which—

Figure 1 is a diagrammatical sectional elevation of the folding mechanism of a web-printing press; and Fig. 2 is an end elevation of Fig. 1 partly broken away.

The folding mechanism is provided as usual, with first-fold rolls 1, 1^a (located at the apex of the former F over which the web is led from the press to the first-fold rolls,)—by which the web is folded longitudinally upon itself before it is severed. It is then passed between the cutting cylinder 2 and the folding cylinder 2^a, which may be provided with tuckers, indicated at T, constructed as usual so that if desired two or more sheets may be collected upon cylinder 2^a before they are passed into the second-fold rolls 3, 3^a. After the desired number of sheets have been severed and collected upon cylinder 2^a, they are discharged from said cylinder, by the well known means and in the well known manner, between the second-fold rolls 3, 3^a, by which the severed sheets are folded transversely upon themselves to half-size papers.

At one side of the second-fold rolls are third-fold rolls 8, which usually are ar-

ranged at right angles to rolls 3, 3^a, and the papers may be directed from the second-fold rolls to the third-fold rolls by the following means:

The roll 3 is provided with tape-channels at intervals in its face, in which channels are guided tapes 6 which, as shown in full lines in Fig. 1, run between rolls 3, 3^a, to and over pulleys 5^a on stub shafts 5^c affixed to arms 5^d mounted on a fixed shaft 5^e. The tapes 6 pass from pulleys 5^a to and over adjustable pulleys 6^a mounted on stub shafts 6^b attached to brackets 6^c adjustably mounted on rods 6^e attached to a fixed shaft 6^f. The brackets 6^c are adjustable on rod 6^e and may be fixed in position thereon by bolts 6^d on brackets 6^c.

On stub shaft 5^c beside pulleys 5^a, are pulleys 5 over which run tapes 7 which are adapted to convey the paper to and over the third-fold rolls 8 and under tucker blade 8^a, which is arranged to be operated in the usual manner so as to pass the papers between the third-fold rolls whereby they are folded to one-quarter size. When the tapes 6 are in the position described and shown in full lines Fig. 1, the sheets will be directed by said tapes 6 onto tapes 7 and carried by the latter to and over third-fold rolls 8.

If the tapes 6 are adjusted to the position shown in dotted lines in Fig. 1, the papers can pass from the second-fold rolls 3, 3^a, in front of upright fingers 4 behind which is located a shaft 4^b carrying rotary flies 4^c by which the one-half-fold papers can be stacked in the usual manner.

If it is not desired to have the papers folded to one-quarter-size, the tapes 6 are slipped off of pulleys 5^a and the pulleys 6^a are moved back on rods 6^e to the position indicated in dotted lines in Fig. 1, and when tapes 6 are in such position the papers will drop from the second-fold rolls 3, 3^a, in front of the rotary fly 4^c. By means of these tapes 6 therefore the operator can readily change the folder to produce papers folded either to half-size or quarter-size, and when running quarter-size-fold papers there is no chance for the papers to become fouled with the rotary fly, or the fingers 4 as the tapes 6 carry the papers positively around and under roll 3^a to the tapes 7, and the papers do not have to jump any spaces between tapes or rollers in order to reach the third-fold rolls.

Having described my invention what I

claim as new and desire to secure by Letters Patent is:

- 5 1. In a folding mechanism, the combination of a pair of folding rolls, means for directing papers thereto; a second pair of folding rolls at right angles to the first folding rolls, and means for carrying papers thereto; with tapes extending between the first pair of folding rolls, and means whereby said 10 tapes can be adjusted either to direct the papers from the first pair of folding rolls to the second pair of folding rolls, or to permit the papers to be discharged away from the first pair of folding rolls.
- 15 2. In a folding mechanism, the combination of cutting and collecting cylinders, a pair of folding rolls adjacent thereto, a second folding device adjacent the folding rolls, a stacker beneath the folding rolls, and an 20 adjustable set of tapes extending between the folding rolls, and adapted when in one position to permit the papers to pass direct to the stacker; and in the other position to direct the papers onto the second folding devices.
- 25 3. In a folding mechanism, the combination of cutting and collecting cylinders, a pair of folding rolls adjacent thereto, a second set of folding rolls adjacent the first 30 folding rolls; a rotary fly beneath the first folding rolls, and an adjustable set of tapes extending between the first pair of folding rolls, and adapted in one position to permit the papers to pass direct to the rotary fly; 35 and in the other position to direct the papers onto the second set of folding rolls.
- 40 4. The combination with a pair of folding rolls, a second folding device adjacent said rolls, a stacking device below said rolls, tapes for carrying papers to the second folding device; adjustable tapes extending between the folding rolls, relatively stationary

pulleys for said tapes below the folding rolls, and adjustable pulleys for said tapes at one side of such rolls, whereby said tapes 45 can be adjusted to permit papers to pass direct to the stacking device or on to the second folding device.

5. The combination in a folding mechanism, of a former, a pair of first-fold rolls 50 at its apex, cutting cylinders adjacent said first-fold rolls; a pair of second-fold rolls; a set of third-fold rolls adjacent the second-fold rolls, and a stacker below the second-fold rolls; with an adjustable set of tapes 55 extending between the second-fold rolls, and fixed and adjustable guide pulleys for said tapes, whereby said tapes can be adjusted either to direct papers from the second-fold rolls to the third-fold rolls, or to permit the 60 papers to pass direct from the second-fold rolls to the stacker.

6. The combination in a folding mechanism, of a former, a pair of folding rolls at 65 its apex, cutting and collecting cylinders adjacent said folding rolls; a pair of second-fold rolls, adjacent the collecting cylinder; a set of third-fold rolls adjacent the second-fold rolls, and a rotary fly stacker below the second-fold rolls; with an adjustable set of 70 tapes extending between the second-fold rolls, and fixed and adjustable guide pulleys for said tapes, whereby said tapes can be adjusted either to direct papers from the second-fold rolls to the third-fold rolls, or 75 direct from the second-fold rolls to the rotary fly stacker, substantially as described.

In testimony that I claim the foregoing as my own, I affix my signature in presence of two witnesses.

HENRY F. BECHMAN.
